(57) **CLAIM**

The ornamental design for a display screen with application icon as shown and described.

DESCRIPTION

FIG. 1 is a front view of a display screen with application icon showing the new design enlarged and without the broken line disclosure for clarity of illustration;

FIG. 2 is a front view of a second embodiment of a display screen with application icon showing the new design enlarged and without the broken line disclosure for clarity of illustration;

FIG. 3 is a front view of a third embodiment of a display screen with application icon showing the new design enlarged and without the broken line disclosure for clarity of illustration;

FIG. 4 is a front view of a display screen with the application icon shown in FIG. 1;

FIG. 5 is a front view of a display screen with the application icon shown in FIG. 2; and,

FIG. 6 is a front view of a display screen with the application icon shown in FIG. 3.

The broken-line perimeter shown in FIGS. 4-6 illustrate a display screen and form no part of the claimed design. The remaining broken lines shown in FIGS. 4-6 illustrate portions of a graphical user interface and form no part of the claimed design.

1 Claim, 6 Drawing Sheets
